UNITED STATES PATENT OFFICE.

JOSEPH PERLMUTTER, OF JERSEY CITY, NEW JERSEY.

BILLIARD-CUE TIP.

1,274,765.

Specification of Letters Patent.

Patented Aug. 6, 1918.

Application filed September 1, 1917. Serial No. 189,263.

To all whom it may concern:

Be it known that I, JOSEPH PERLMUTTER, a citizen of the United States, residing at Jersey City, in the county of Hudson, State 5 of New Jersey, have invented a new and useful Improvement in Billiard-Cue Tips, of which the following description, in connection with the accompanying drawings, is a specification, like characters in the drawings representing like parts.

This invention relates to an improvement in billiard cue tips and has for its object to provide a cue tip which may be quickly attached to and detached from the ends of 15 billiard and pool cues without the use of glue or other adhesive substance, the device being adapted for quickly attaching to the end of cues with a special cue tip holder or socket, such as is shown and claimed in my application 20 for patent on an improvement in cue tip sockets or holders, filed concurrently with this application Serial No. 189,264, filed Sep. 1, 1917, thereby saving the loss of time, labor and the use of the cues, which 25 follows attaching cue tips with glue or adhesive substance in the old way.

Other objects will in part be obvious and in part pointed out hereinafter.

In the accompanying drawings:

30 Figure 1 is a side elevational view of the device, of the cue tip holder, in which it is retained, and of a portion of the hitting end of a billiard cue.

35 Fig. 2 is a side elevational view of the cue tip, showing the bottom or flanged base portion resting and secured in one half of the cue tip socket or holder, and a sectional view of a portion of the hitting end of the cue showing the manner in which the cue tip 40 holder is secured and retained therein.

Fig. 3 is a side elevational view of the completed device.

45 Fig. 4 is a vertical sectional view of the two main portions of the cue tip, showing the flanged base portion and the rabbetted top or head portion.

50 Fig. 5 is a vertical sectional view of the top or head portion of the device and a modified form of the base portion, having two annular flanges anchored or retained in the cue tip holder or socket, a section of which is broken away to show the formation of the modified base.

55 In the drawings the numeral 1 represents the head or hitting end of the device, being the portion that comes immediately in con-

tact with the billiard ball when it is struck by the cue and is preferably made of a single piece of leather as in Fig. 3, but if desired it may be of a laminated construction as indicated in Figs. 4 and 5, the head portion 1 formed of a soft springy leather, and the under portion 2 of a hard leather or other suitable material.

The base portion of the device 3 has its 65 upper surface 10 formed integrally with a centrally located cylindrical protrusion 11 adapted to fit into a centrally located cylindrical recess 12, formed in the head portion 2, so that when the two portions are attached as in Fig. 3, the sides 13, 14, are parallel and give an unbroken cylindrical formation. The lower portion 4 of the base portion 3 is flanged, the upper side 8, of the flange being parallel with the under-surface 75 9 of the main portion 3.

It will be understood, however, that the invention is not limited to this construction as it may be desirable to supply two flanges at the base portion as illustrated at 16, 15, 80 Fig. 5. It will be noted that both ends of the base member 3 are cylindrical, the flanged portion 4 being of a smaller diameter, rendering it capable of being retained within the cue tip holder such as illustrated. 85 It will be seen that the assembly of the tip, tip holder, and cue, as illustrated in Fig. 1, presents a smooth unbroken cylindrical unit.

It will be noted that the cylindrical protrusion 11, acts as a guide to hold the two 90 portions of the device in proper position and relation when attached, and also gives added strength to the head portion 1 so that it can not readily be detached from the base section by reason of side blows, when in use. 95

Having thus described my said improvement, I claim as my invention and desire to secure by Letters Patent under this specification:

1. In a cue tip, the hitting member having 100 a cylindrical recess on one end, the base member having a cylindrical tongue on one end to register within the recess in the hitting member, the other end being formed as a flange for securing the device on the end 105 of a billiard cue.
2. A cue tip comprising a head or hitting portion and a base portion, the base portion formed, on one end, to dowel into the head portion and having its free end shaped in 110 the form of an annular flange.
3. In a cue tip, the head or hitting mem-

ber, comprising a hard and a soft layer of similar material, the soft layer shaped for contact with billiard balls, the hard layer containing a cylindrical recess, a base portion, made of fiber or other suitable material, formed with a cylindrical neck or protrusion on one end adapted to register within and be permanently attached to the head member, the other end of the base member forming an annular flange, adapted to be secured to the end of a billiard cue, by suitable retaining means.

4. In a cue tip, the head or hitting member, comprising a hard and a soft layer of similar material, the soft layer shaped for contact with billiard balls, the hard layer containing a cylindrical recess, a base portion, made of fiber or other suitable material, formed with a cylindrical neck or protrusion on one end adapted to register within the head member, the cylindrical walls in close contact, the cylindrical ends slightly separated to form an air cushion, the other end

of the base member formed as an annular flange, adapted to be secured to the end of a billiard cue by suitable retaining means.

5. In a cue tip, comprising two main members, the hitting member, cylindrical in shape, having one end formed like the segment of a sphere, the other end having a cylindrical recess, the base member, cylindrical in shape, one end provided with a cylindrical tongue and adapted to register integrally with the recessed end of the hitting member, to form an unbroken cylindrical unit, the opposite end of the base member formed as an annular flange, the circumference of which is less than that of the main member.

In testimony whereof I have signed my name to this specification in the presence of two subscribing witnesses.

JOSEPH PERLMUTTER.
